UNITED STATES PATENT OFFICE

90,984

DESIGN FOR A SHOW CASE

Herbert C. Illium, Wilmette, Ill., assignor to The Wahl Company, Chicago, Ill., a corporation of Delaware

Application August 24, 1933. Serial No. 49,104

Term of patent 7 years

To all whom it may concern:

Be it known that I, HERBERT C. ILLIUM, a citizen of the United States, residing at Wilmette, in the county of Cook and State of Illinois, have invented a new, original, and ornamental Design for a Show Case, of which the following is a specification, reference being had to the accompanying drawing, wherein

Fig. 1 is a front perspective view of a show case showing one aspect of my new design;

Fig. 2 is a side perspective view of a show case showing another aspect of my new design; and
Fig. 3 is a top view of the show case illustrated in Figs. 1 and 2.

I claim:

The ornamental design for a show case, substantially as shown.

HERBERT C. ILLIUM.
